ROLLING MILL ADJUSTING APPARATUS

Giuseppe Cozzo, New York, N. Y., assignor to
Hydropress, Incorporated, New York, N. Y., a
corporation of Delaware

Application February 14, 1946, Serial No. 647,529

7 Claims. (Cl. 80—56)

1

This invention relates to rolling mills and particularly to a means for accurately adjusting the rolls therein so as to control closely the thickness of the material or foil being rolled.

A conventional rolling mill has at least two rolls with end bearings supported in suitable end frames. A screw down or equivalent adjustable abutment member is located in each end frame to limit the movement of the two rolls away from each other and thus control the finished thickness of material being rolled. Various combinations of rolls may be employed such as back- ing rolls for the rolls actually contacting the material being rolled.

The screw down member in the past has been adjusted usually by engaging a wrench therewith and directly exerting force thereon or by tapping the wrench with a hammer. As a result, it has been difficult to make adjustments accurately and especially when only small changes are required. This particularly is true when the screw down member has had considerable axial load exerted thereon.

In accordance with the present invention, a block is associated eccentrically relative to the adjusting screw and hammers are arranged for exerting blows selectively in either direction on the block so as to cause a small angular movement in the desired direction of the screw with each blow of the hammer. The hammers can be supported on a heavy plate concentrically mounted relative to the adjusting screw and means provided so that the plate and hammers can center themselves relative to the block after each small movement of the block and screw. A series of relatively rapid substantially uniform blows are given to the block, the length of time of said series governing the amount the adjusting means is moved or rotated.

The invention also may be used for other purposes where it is desired to produce a movement composed of a series of small movements. Various arrangements of the hammers, types of vibrators, and details of construction may be used, the following description and drawings merely being exemplary of one form of the invention.

In the drawings:

Fig. 1 is a plan view of one form of the apparatus.

Fig. 2 is a section taken along the line 2—2 of Fig. 1, the screw shank being shown in full.

As mentioned previously, rolling mills have at least two rolls between which the material to be shaped is passed. At the ends of each of these

2

rolls there is a bearing arrangement which is normally supported in a suitable type of upright frame, the frame being designed so as to absorb the rather high stresses frequently caused therein as the material is passed through the rolls. The lower set of bearings normally is positioned vertically directly by said frame or support and an adjustable abutment limits upward movement of the upper roll away from the lower roll as material is passed therebetween thus governing the final thickness of the material being shaped. In some types of mills, there are rolls placed outside of the shaping rolls themselves and the invention will apply thereto as well as to the case where only one pair of rolls is used. In addition thereto, the abutment for the lower roll can be made adjustable.

One of the mill housings 20 is shown diagrammatically with an adjustable screw down member 21 mounted therein, the lower point 22 of said screw being adapted to contact the upper roll bearing, or other adjusting means, of the mill in any suitable manner. Arm 3 is made integral or non-rotatably fastened to the shank 25 of adjusting screw 21, arm 3 having a hammer block 4 mounted thereon, said hammer block being spacedly located from the center line of the adjusting screw 21 and therefore eccentrically mounted relative thereto. Heavy frame or plate 5 is rotatably mounted relative to the adjusting screw and block carrying arm 3 by means of supporting bracket 7 and pin 8 depending therefrom, said pin 8 being rotatable in aperture 23, said aperture being substantially aligned with the center line of the adjusting screw 21. Plate 5 has a recess 19 in which can be located block supporting arm 3, there being sufficient clearance provided so that block supporting arm 3 is oscillatable in said recess relative to plate 5.

Hammers 11A, 11B are carried by spring leaves 9A, 9B, respectively, said spring leaves being mounted on bracket 6 carried by plate 5. The hammer may be fastened to the springs by means of screws 12 or in any suitable fashion and bolts 10 can be employed to fasten the two spring leaves 9A, 9B to bracket 6. Block carrying arm 3 is centered in recess 19 by means of yieldable blocks 13A, 13B, said blocks preferably being of rubber although springs or other suitable resilient devices can be used to center the block carrying arm 3 relative to recess 19.

In the form shown, the operating means for the hammers is provided by two electric vibrating motor stators 14A and 14B and their respective armatures 17A and 17B mounted on spring leaves

9A and 9B. The stators have coils 16A and 16B wound thereon, said coils being connected through suitable control means to a source of alternating current and arranged so that either stator may be energized or so that the stators can be energized in such a manner as to cause rotation of the screw 21 in the desired direction.

When a screw 21 is to be turned in one direction, coils 16A may be energized, for example, which will cause a vibration of spring leaf 9A. Hammer 11A will thereby impart a series of rapid blows to hammer block 4 tending to turn the arm 3 in a counterclockwise direction (Fig. 1). The plate 5 is made sufficiently heavy so that the inertia thereof relative to the hammer 11A, block 4, and arm 3 will cause plate 5 not to rebound or move in a clockwise direction as the hammer strikes the block, resilient member 13B being compressed instead. The energy stored in the resilient member 13B will tend to center plate and recess 19 relative to the arm 3 as the action continues, so that arm 3 and plate 5 will continue a slow rotation until the power is cut off to coils 16A. Similarly, if rotation is desired in a clockwise direction, coils 16B can be energized.

It is apparent that other equivalent types of vibrating elements may be used in place of those shown such as a conventional rotating motor and cam (not shown), or some type of conventional mechanical vibrator (not shown). The vibrator should be one which imparts a blow to the hammer block so as to move the adjusting screw a small amount with each blow. These and other modifications may be made in the form and construction shown without departing from the spirit of the invention or scope of the appended claims.

What is claimed:

1. In combination; a rotatable adjusting means mounted on a device to be adjusted; blow imparting means contactable with said rotatable adjusting means for rotating said adjusting means; a support carrying said blow imparting means and mounted on said adjusting means, said support being rotatable relative to said device to follow said adjusting means upon rotation thereof by said blow imparting means, said support having sufficient inertia so as not to move in a direction opposite to that of the blows of the blow imparting means relative to the adjusting means as the blows are being imparted; and a resilient means connecting said rotatable adjusting means and said support so that upon operation of said blow imparting means, said adjusting means can be rotated as desired.

2. In combination, a rotatable adjusting means, an arm extending radially therefrom with a block thereon, blow imparting vibrating hammers selectively operable to impart blow to said block in either direction as desired, a rotatable carrier supported on said adjusting means carrying said blow imparting hammers in proximity to said block, and hammer actuating mechanism adjacent said hammers for vibrating the same to hit said block and rotate said adjusting means, said carrier having means maintaining said vibrating means in proximity to said block.

3. In combination; a rotatable adjusting means; an arm extending therefrom with a block thereon; a pair of springs and hammers thereon, said hammers straddling said block; a plate carrying said springs, said plate being rotatable relative to said adjusting means; and means to selectively vibrate said hammers.

4. In combination, a rotatable screw threaded adjusting means; an arm extending from said adjusting means, said arm having a block eccentrically located relative to said adjusting means; a heavy plate rotatably supported on said adjusting means; a pair of springs and hammers carried by said springs mounted on said plate, said hammers straddling said block; a vibrator for each hammer selectively operable to actuate one of said hammers, and a resilient connection between said plate and arm, the inertia of said plate being such that the arm is moved by a blow of the hammer and the plate follows the arm thereafter.

5. In combination, a rotatable screw threaded adjusting means; an arm extending from said adjusting means, said arm having a block eccentrically located relative to said adjusting means; a heavy plate rotatably supported on said adjusting means; a pair of springs and hammers carried by said springs mounted on said plate, said hammers straddling said block; an alternating current vibrator for each hammer selectively operable to actuate one of said hammers, and a resilient connection between said plate and arm, the inertia of said plate being such that the arm is moved by a blow of the hammer and the plate follows the arm thereafter.

6. In an adjusting device combination, a rotatable adjusting means having a blow receiving portion, vibratable mechanical means contactable with said blow receiving portion of said adjusting means for imparting blows thereto and rotating said adjusting means, said mechanical means being held on a support movable relative to said adjusting means, and a control connected to said vibratable mechanical means controlling the direction and number of blows imparted thereby to said blow receiving portion, so as to selectively rotate said adjusting means.

7. In an adjusting device combination, a rotatable adjusting means having a blow receiving portion, vibratable mechanical hammers contactable with said blow receiving portion of said adjusting means for imparting blows thereto, so as to rotate said adjusting means, a movable support carrying said blow imparting hammer means, said movable support rotating with said adjusting means and being movable relative thereto, so as to hold said blow imparting hammers in close proximity thereto, and means connected with said hammers for operating the same.
